(57) **CLAIM**

The ornamental design for a razor component, as shown and described.

DESCRIPTION

FIG. 1 is a perspective view of a design for a razor component for the present invention;
FIG. 2 is a front view thereof;
FIG. 3 is a back view thereof;
FIG. 4 is a top view thereof;
FIG. 5 is a bottom view thereof;
FIG. 6 is a left side view thereof;
FIG. 7 is a right side view thereof; and,
FIG. 8 is another perspective view thereof.
The dash broken lines are directed to the environment and are for illustrative purposes only and form no part of the claimed design.
